UNITED STATES PATENT OFFICE.

SYLVESTER KUBIAK, OF CHICAGO, ILLINOIS.

RENEWABLE FUSE PLUG.

Application filed October 23, 1922. Serial No. 596,363.

To all whom it may concern:

Be it known that I, SYLVESTER KUBIAK, a citizen of the United States, and a resident of Chicago, in the county of Cook and State of Illinois, have invented a new and useful Improvement in Renewable Fuse Plugs, of which the following is a full, clear, and exact description.

My invention relates to improvements in renewable fuse plugs, and more particularly to that type of fuse plug in which the fusible element may not be intentionally rendered inoperative easily, and it consists in the combinations, constructions, and arrangements herein described and claimed.

An object of my invention is to provide a device of the character described in which the fusible element consists in a unit which may be quickly and easily replaced in the plug.

A further object of my invention is to provide a device of the character described in which means is provided for preventing the intentional introduction of a relatively heavy conductor in place of the fusible element to willfully render the fuse plug inoperative. In the ordinary renewable fuse plug, it is relatively easy to introduce a copper wire or a heavy lead wire in place of the strip or lighter wire already provided.

A further object of my invention is to provide a device of the character described in which the fusible element of the plug is disposed directly below a mica window and may be readily observed even though the mica may be somewhat coated with the volatilized elements of the fused strip.

A further object of my invention is to provide a device of the character described which is simple in construction, easy to manufacture, and thoroughly practical commercially.

Other objects and advantages will appear in the following specification, and the novel features of the invention will be particularly pointed out in the appended claims.

My invention is illustrated in the accompanying drawings, forming part of this application, in which—

Figure 1 is a top plan view of an embodiment of my invention,

Figure 2 is a sectional view along the line 2—2 of Figure 1,

Figure 3 is a sectional view along the line 3—3 of Figure 1, and

Figure 4 is a perspective view of the renewable fuse plug element.

In carrying out my invention, I make use of a porcelain body member 1 having a bore 2 disposed longitudinally therethrough. The bore 2 is provided with an enlarged portion 3 adjacent to its upper end. A rectangular cavity 4 is provided in the top wall of the body member 1 and the enlarged portion 3 of the bore 2 communicates therewith. A binding screw 5 is disposed in the bore 2 with its head 6 extending exteriorly thereof. The screw 5 is provided with an enlarged threaded portion 7, which threaded portion is arranged to extend within the enlarged portion 3 of the bore. In assembling my device, I introduce soft metal, such as babbitt 8, into the bore 3 and tamp it slightly at the bottom of the bore so as to provide an effective collar by means with which the threaded portion 7 of the screw 5 may contact and thereby accidental displacement of the screw 5 is prevented. A metal washer 9 is introduced intermediate the head 6 of the screw 5 in the body member 1 so as to insure an effective electrical contact with the center electrode of the ordinary type of lamp socket when the plug is introduced therein.

The body member 1 is provided on one side thereof and adjacent one end of the rectangular cavity 4 with a longitudinal groove 10 extending the entire length of the body member 1 and communicating at its upper end with the cavity 4. A standard screw plug shell 11, which is formed so as to enter and engage with the ordinary type of standard light socket, is disposed concentric with the body member 1 and has secured thereto by means of a screw 12 a binding plate 13. The binding plate 13 is secured to the inner side of the shell 11 and occupies a portion of the groove 10. The purpose of having the groove 10 extend the entire length of the body member 1 is so that the shell may be placed upon the body member after the binding plate 13 has been

secured thereto. This structure facilitates the quick assembly of the device. The binding plate 13 is provided with a binding screw 14, which screw is inserted in a 5 threaded opening 15 extending transversely through the plate. A portion of the body member 1 at the upper end of the groove 10, as shown at 16, is cut away so that the binding screw 14 may not be retarded in its 10 longitudinal movement.

The body member 1 is provided with a metal cap 18 which is arranged to closely fit the top of the body member and is provided with a window 19 therethrough, by 15 means of which the fusible element in the cavity 4 may be observed. A mica disc 19^a disposed immediately below the cap 18 serves as a protection for the fusible element as well as to prevent the escape of the 20 portions of element when it is fused. Means for securing the cover 18 to the body member 1 is provided in notches 20 (see Figure 3) disposed in the periphery of the top portion of the body member and 25 in which inwardly bent portions 21 in the side walls 22 of the cap 18 may be received. A groove 23 communicating with the notch 20 provides a means for the inwardly bent portion 21 to enter the notch 20.

30 The renewable fuse element employed in my device is constructed of a strip 24 of fusible metal. The composition of this metal is well known in the art and is in use at the present time in most plug fuses. The strip 24 is provided with a reduced portion 25 intermediate its length. One end of the strip 24 has a relatively deep recess 26 in the edge thereof. The recess 26 is sufficiently wide to admit the binding screw 14 (see 35 Figure 2). The opposite end of the strip 24 has secured thereto a threaded lug 27. The threads of the lug 27 are arranged to engage with the enlarged threaded portion 7 of the screw 5, as shown in Figure 2. 40 Means for supporting the relatively soft fusible strip 24 is provided in an insulating strip 28 which may be mica or any other well known substantially rigid insulating material. The strip is bent so that the lug 27 is on the underside of the strip 28, substantially midway of its length, and the portion having the recess 26 is bent up over the top of the strip 28 and downwardly in 45 parallel relation with the lug 27. The entire fusible element which is a unit in itself, may therefore be handled with little danger or damaging the relatively delicate strip 24 and is so constructed as to maintain its approximate shape when not in the plug. 50 The carrying capacity of the fusible element of course is regulated by the sectional area of the reduced portion 25 of the strip and 55 may be made relatively high or relatively low, dependent upon the particular need.

From the foregoing description of the 65 various parts of the device, the operation thereof may be readily understood. Let us assume that the plug is inserted in a standard fuse plug base having a standard receptacle, and that the current in passing 70 through the plug has passed the maximum amperes, and as soon as the strip 24 has become fused at its reduced portion 25, an inspection of the plug as it is seen in Figure 75 1, will tell the observer beyond the question 80 of a doubt that the strip 24 is no longer intact, since the strip is disposed immediately under the transparent mica window 19^a. In spite of the fact that the window may be 85 slightly discolored from the heat of the fusing strip, the strip may be seen.

To replace the fusible element, the cover 18 is removed by turning it slightly to the left or to the right and elevating it through the grooves 23 (see Figure 3). The binding screw 5 is then operated so that the enlarged threaded portion 7 may disengage the lug 27 and the binding screw 14 is turned so that its head may move out of contact with the strip 24 adjacent the recess 90 26. The entire fusible element may then be removed and a new element replaced.

One of the most important features of my invention, as will be seen at this time, 95 is that the fusible element must have a certain predetermined shape, otherwise no electrical connection may be made between the binding screw 5 and the shell 11. In my present invention, it is not possible to introduce a wire into the plug and wrap each 100 end about the terminals of the plug as may easily be done in a great many of the ordinary type of renewable fuse plugs. This is because one terminal, i. e., the binding screw 5, is disposed within a bore considerably below the mouth thereof and the annular space between the terminal and the adjacent walls of the bore is so small that introduction of a relatively heavy wire or the 105 like is practically impossible.

I claim:

1. A device of the character described comprising a body member having a cavity in the top wall thereof, a bore extending vertically through said body member and communicating at its upper end with said cavity, a pair of fuse terminals, one of said terminals being disposed within said bore, but not exposed in said cavity, and a fusible element, one terminal of which is adapted to be connected to the terminal in said body member that is disposed within the bore, and the other terminal of which is connected to the remaining terminal on said body member.

2. A device of the character described comprising a body member having a cavity in the top wall thereof, said body member

having a bore extending vertically there-through communicating at its upper end with said cavity, a pair of fuse terminals, one of said terminals being disposed within said bore but not exposed in said cavity, that portion of said fuse terminal within said cavity being enlarged, said fuse terminal associated with said bore also having an enlarged portion at its opposite end, whereby

said terminal may rotate in said bore but 10 may not become dislodged from said bore, and a fusible element, one terminal of which is adapted to be connected to the outer portion of said fuse terminal in said cavity, and the other terminal of which is connected 15 to the remaining terminal on said body member.

SYLVESTER KUBIAK.
